UNITED STATES PATENT OFFICE

FÉLIX MOREL, OF FAYETTAS, DORDOGNE, FRANCE, ASSIGNOR TO ANCIENS ETABLISSEMENTS R. CORNELY & CIE. (SOCIÉTÉ ANONYME), OF PARIS, FRANCE

SEWING MACHINE

Application filed October 21, 1926, Serial No. 143,261, and in France January 28, 1926.

It is an observed fact that in the known machines for embroidering, sewing and open-work stitching, of the crank type, the presser foot which draws forward the textile fabric is rigidly secured to a feed bar by reason of the well-known functioning of the head plate, is caused to oscillate upon two horizontal axes perpendicular to one another, and is also given a vertical reciprocating motion, during which it is guided by a feed bar bearing which is slidable on a vertical tube. To provide for the oscillation of the said bar upon these two rectangular horizontal axes, the said feed bar bearing must be given a special form.

In my prior patent application, Serial No. 123,758, filed July 20th, 1926, I described in detail the disadvantages inherent in the use of such machines which are provided with feed bar bearings having the shape of a double funnel, i. e., the rapid wear of the said bearing and the irregularity of the stitching, and I described a guiding arrangement by which all such inconvenience is obviated. But this construction is only applicable with facility to machines of a relatively large output, that is to say, having a considerable size.

The present invention has for its object to obviate the aforesaid disadvantages by other means.

The following description, with reference to the appended drawings which are given by way of example, sets forth the manner in which the said invention may be carried into effect.

Fig. 1 is an elevational view of my improved feed bar carrier. Figs. 2 and 3 are corresponding end and plan views, respectively. Fig. 4 is an end view of a detail, and Fig. 5 is the corresponding plan view. Fig. 6 is an elevational view of a modified construction, and Figs. 7 and 8 are corresponding views, respectively in end elevation and in plan. Figs. 9 and 10 are respectively an elevational and a plan view of a detail of construction.

In the first embodiment of the invention, the feed bar carrier C is pierced with two smooth apertures in which are engaged the respective screws W W' which are terminated

by two smooth cylindrical portions and serve to support the feed bar A, whereby it is enabled to pivot on the axis X—X.

The said feed bar carrier C is further supported by a journal D in which the cylindrical shaft I of the said feed bar carrier is rotatable. The bearing D is rigidly secured to the slide of the presser foot, which is vertically movable, said slide not being shown in the drawings.

Within the feed bar carrier C is mounted a collar E which is shown in Figs. 4 and 5 in end elevation and in plan view. The two faces f f' of the said collar are cylindrical and the two flat faces g g' carry the cylindrical trunnions e e'.

The collar E is pierced with an aperture of such size that it will be slidable without play upon the guide tube B of the machine. By reason of the shape of the collar E, the feed bar carrier C is made in two parts, for milling purposes, and the end-plate C' is secured thereto by means of the screws V₁ V₂ V₃ V₄.

The collar E plays the part of a rigid shaft for the whole arrangement, since it is mounted without play upon the tube B, and it guides the feed bar carrier C which is maintained upon the axis Y—Y by the two trunnions e e', and also by reason of the cylindrical shape of the two faces f f' of the collar E.

The feed bar carrier C is maintained upon the axis X—X of the member E by the two flat bearing surfaces M N and m n coacting with the flat faces g g'' of the collar E, and upon the axis Z—Z of the tube, solely because the collar E is slidable with light friction on the said axis.

The feed bar carrier C, by reason of its two apertures coacting with the respective trunnions e and e', will suitably center the collar E, so that the two axes Y—Y of each of these two members will coincide.

The members E, C and C' will thus have very simple geometrical forms, and may therefore be milled with great accuracy.

When the feed bar A oscillates on the axis X—X, the screws W and W' will act as pivots for the oscillation; when the said feed bar A oscillates on the axis Y—Y, the feed

bar carrier C will rotate by its shaft I, in the journal D, and the members E and C will move relatively to one another, due to their cylindrical sides and to the trunnions e and e' (which latter would be sufficient).

It will be thus observed that by its present construction, the feed bar carrier C, while executing its movements of oscillation on X-X, Y-Y and all other intermediate axes, cannot become displaced along the axis Y-Y or X-X, and that the point O will remain constantly on the axis Z-Z when by reason of the functioning of the machine the feed bar carrier C is given a vertical reciprocating motion.

With the present construction, the wear of the parts is a minimum, since the cylindrical sides of the members E and C can be given a large bearing surface.

In the second form of construction, the feed bar carrier F is maintained in the manner above described. The difference in the arrangement resides in the fact that the member G (substituted for the member E) is a portion of a sphere which is pierced with an aperture of such size that it will be slidable without play upon the guide tube of the machine (not shown in Figs. 6, 7 and 8). The member F is therefore made in two parts for milling purposes, these parts being secured together by the screws U₁ U₂ U₃ U₄.

The aforesaid arrangements are given solely by way of example, and the forms, dimensions and detail dispositions may be modified in any suitable manner without departing from the principle of the invention as comprehended within the scope of the appended claims.

What I claim is:

1. A feed bar bearing for sewing machines comprising, in combination, a feed bar carrier, means associated with said carrier for universally supporting said feed bar, a vertically disposed guide tube extending through said carrier, a guide collar slidably mounted on said tube without play, and an articulation between said collar and said carrier.

2. A feed bar bearing for sewing machines comprising, in combination, a feed bar carrier, means associated with said carrier for universally supporting said feed bar, a vertically disposed guide tube extending through said carrier, a guide collar slidably mounted on said tube without play, and complementary surfaces of a solid of revolution disposed on said collar and said carrier for permitting relative oscillatory displacement between said collar and said first-mentioned means.

3. A feed bar bearing for sewing machines comprising, in combination, a feed bar carrier, means associated with said carrier for universally supporting said feed bar, a vertically disposed guide tube extending

through said carrier, a guide collar slidably mounted on said tube without play, a pair of concave cylindrical surfaces on said carrier, a pair of convex cylindrical surfaces on said collar engaging said first-mentioned surfaces and a pair of trunnions disposed on said collar at right angles to the cylindrical surfaces thereon engaging said carrier thereby permitting relative oscillation between said carrier and said first-mentioned means about said trunnions.

4. A bearing according to claim 3 in which the coacting surfaces adjacent said trunnions are flat.

In testimony whereof I have signed this specification.

FÉLIX MOREL.
